UNITED STATES PATENT OFFICE.

ALEXANDER McCULLOCH, OF GOVAN, SASKATCHEWAN, CANADA.

GARAGE DOOR.

Application filed July 3, 1920, Serial No. 393,999. Renewed October 27, 1922. Serial No. 597,406.

To all whom it may concern:

Be it known that I, ALEXANDER McCULLOCH, a citizen of the Dominion of Canada, residing at Govan, in the county of Humboldt and Province of Saskatchewan, have invented certain new and useful Improvements in Garage Doors, of which the following is a specification.

This invention relates to improvements in garage door operating means and provides an automatic means whereby the doors will be swung open on the approach of an automobile.

The object of my invention is to provide a means whereby doors will be automatically thrown open on the approach of an automobile.

A further object of my invention is to provide a means for locking said doors in open position so that they will not slam shut when the automobile is only partly in the garage.

A further object is to provide a means for releasing the locking means when the rear of the automobile has passed the locked doors.

A still further object is to provide a means for releasing the locking means when the automobile is being taken out of the garage and it has passed out through said doors.

With these and other objects in view, the invention consists in the construction, combination and arrangement of parts as will be hereinafter fully described, illustrated in the accompanying drawings, and pointed out in the claim hereunto appended.

Figure 1 is a detail plan view.

Figure 2 is a detail side view partly shown in section.

Figure 3 is a detail view of the spring operating means.

Figures 4 and 5 are detail views of the door operating means.

Figure 6 is a detail view of the lug hinging the upper end of the said doors.

Figure 7 illustrates the unlocking means for said doors while in open position.

Figure 8 illustrates the automatic releasing means for said doors while in open position.

Referring to the drawings like numerals designate like parts in the various drawings.

10 indicates the garage frame. 11 indicates floor. 12 indicates the approach to the ga-

rage in which are provided longitudinal slots 14, 15 and 16 indicate members hingedly connected to one end, as at 17, to the approach 12 while their other ends are provided at the under side with downwardly extended sockets 18, which sockets are threaded interiorly. Suitably journalled in the journals 19 is a shaft 20 having its upper end threaded as at 21 adapted to be received into the socket 18. Adjustably positioned on the shaft 19 is a double arm member 22. Its inner end is hingedly connected to an arm 23. The opposite end of the arm 23 is hingedly connected in a U-shaped member 24. The U-shaped member 24 is provided with a transverse opening and is reciprocally positioned on a rod 25. The rod 25 is suitably mounted on a frame 26 in brackets 27. Positioned on the rod 25 is a coil spring 28 adapted to tension the U-shaped member 24 as indicated by the arrow in Figure 3. The opposite end of the double arm 22 is connected to an arm 29, which is provided with a turn buckle 30 for adjusting it to various lengths.

Suitably positioned in the frame 10, I provide rods 32, having their upper ends suitably attached to the lower end of the doors as at 33 so that the door will hinge thereon. The door is hinged at its upper corner as shown at 33' in Figure 6. The rod 32 is provided with a radially extending arm 34, the free end of which attaches to the end of the arm 29. On the approaching of an automobile, the wheels will be guided so as to run up the members 15 and 16. These members may be pressed down at their upper end, so that the sockets 18 will turn the threaded portion 21 of the shaft 20. This will turn the double arm 22 so that the arm 23 will pull the U-shaped member 24 in the direction of the arrow, Figure 3, while the arm 29 will push the arm 34 in the direction of the arrow, Figure 4, which will turn the doors from closed to open position. In garage doors, there is generally a locking means at the bottom of the door such as a pin 48 which can be easily pulled up from the inside of the door.

The member 16 is provided at its hinged end with a plate 40, having an opening 41 which opening extends through the member 16. 42 is a trip member tensioned upwardly by a coil spring 43 suitably positioned in the opening 41. The lower end of the trip

member 42 is adapted to strike one end of the bell crank 44. The opposite end of the bell crank is attached to a cable 45, which cable is attached at its opposite end to a bell crank 46. The opposite end of this bell crank 46 is adapted to press upwardly on a tension pin 47. The pin 47 is positioned under the opening in which the pin 48 of the door is positioned when the pin 48 is in locked position. As the automobile passes over the member 16, it will press the trip member 42 downwardly, which will act through the respective parts in pressing the lock pin 48 of the door upwardly from its locked position. The weight of the automobile on the members 15 and 16 will now turn the doors open as previously described.

Suitably positioned on the floor 11 inside the garage, I provide a plate 50, having a central opening over an opening in the floor 11. A plate 51 is positioned on the under side of this opening and has an opening therein.

52 are brackets supported from said plate 51, in which are hingedly positioned bell cranks 53 and 54. When the doors are opened, the pin 48 carried by one of the doors will drop into the opening through the plate 50 and to provide a means for disengaging the pin 48 with the plate 50, I provide a pin 55 tensionally held in the floor and being provided with a flange near its lower end. The bell crank 54 has a cable 56 attached to one end while its opposite end 35 is bifurcated and fits over the flanged end of pin 55. This cable 56 is attached to a suitable trip member 57 similar to trip member 42. This trip member is positioned to be passed over by the wheels of the automobile when in the garage and will cause the pin 55 to be pressed upwardly, thus dis-

engaging the locking pin 48 of the door, so that the tension spring 28 will re-act to close the doors.

After taking the automobile out, I provide a means whereby the travel of the automobile will automatically release the pin 48 and allow the doors to close. Referring to Figure 8, I provide a trip member 60 having tensioned pins 61 and 62 positioned under each respective side. When the automobile travels up the approach, the member 60 is pressed in the direction of the arrow Figure 8. When the automobile is being backed out of the garage, the member 60 is pressed in the opposite direction to the arrow Figure 8 and the pin 62 will press one of the arms of the bell crank 63, which will pull the cable 64. The cable 64 is connected at its opposite end to the bell crank 53 so that the pin 55 will be pressed upwardly to release the pin 48 allowing the doors to close.

What I claim as new is:

In combination with a pair of garage doors, a pin locking means at the lower ends 65 of one of said doors, an inclined platform to said doors depressible longitudinal members hingedly connected at one end in said inclined platform, release means in one of said longitudinal members for releasing said locking pin, a means for opening said doors, a means for retaining said doors in open position, a means on the other of said longitudinal members for disengaging said retaining means, and a means on the other side of 70 the door for releasing said retaining means.

In testimony whereof, I affix my signature in the presence of two witnesses.

ALEX. McCULLOCH.

Witnesses:

A. C. BIBB,
JAMES WALKER.
